ENVELOPE

Edmund William Hayes, Arlington, Mass.

Application December 16, 1932
Serial No. 647,645

6 Claims. (Cl. 229—72)

My invention relates to an improvement in so-called duplex envelopes employed for the distribution of mailable matter under the lower class postage rates.

Under the postal regulations, the transmission of certain classes of mailable matter is permitted in the so-called duplex envelopes where the latter are unsealed, to permit inspection of the contents of the envelopes. To obtain the benefits intended under these regulations, a principal object of this invention is to employ a dual envelope assembly comprising a unit for simultaneous mailing, yet permitting separation of the component parts of the unit for the independent transmission through the mails of only one of the envelopes.

In carrying my invention into practice, I use two envelopes, varying in size, one of which, preferably the larger, carries the name of the addressor or sender and is formed to receive the other envelope carrying the name of the addressee, immediately over the addressor's name. In this manner, when the unit is mailed, the name of the addressee only is in view; removal of the addressee envelope exposes the name of the addressor or sender on the larger envelope to permit remailing of the latter.

Other objects of the invention will be apparent from the following description of the present preferred form thereof, taken in connection with the accompanying drawing, wherein

Fig. 1 is a front elevational view of an addressor envelope, made in accordance with my invention, with the addressee envelope removed;

Fig. 2 is a similar view of the unit envelope, showing a corner of the addressee envelope upturned; and

Fig. 3 is a detailed, fragmentary, cross-sectional view of the envelope unit taken on the line 3—3 of Fig. 2, looking in the direction of the arrows.

In the drawing, wherein for the purpose of illustration is shown a preferred embodiment of my invention, an envelope assembly or unit is illustrated, which consists of two envelopes, one of which, designated 4, is the addressor envelope, while the other, designated 5, is the addressee envelope. Preferably the envelope 4 is larger to accommodate third or fourth class mailing matter and is equipped with a conventional closure flap 6, which may be secured to the body of the envelope by suitable fastening means 7. The front face of the envelope 4 has indicia 8 thereon, which in the present instance, consists of the name and address of the addressor. A series of

diagonal slits 9 is formed in the front wall of the envelope 4, beyond the zone covered by the indicia 8. Portions of the envelope bordering the slits 9, and indicated on the drawing at 10, are preferably marked or colored, so as to stand out prominently, providing corner flaps for a purpose more fully hereinafter set forth. Also, a dictionary legend, indicated in the drawing at 11, is preferably arranged on the front wall of the envelope 4, directly above the slits 9, formed around the indicia 8. One terminal of the legend has an arrow 12 leading therefrom and extending downwardly into the zone of the slits 9, adjacent the indicia 8.

The addressee envelope 5 may be of conventional construction and is of a size to permit the corners 13 of the envelope to be fitted or trained through the slits 9, as shown in Fig. 2 of the drawing. The addressee envelope is adapted to receive indicia 14, representative of the name and address of the addressee, in order to be exposed to view when the addressee envelope is superimposed on the front wall of the envelope 4, over the indicia 8.

In use of this envelope, mailable matter is inserted in the addressor envelope 4 and in the addressee envelope 5, the latter being positioned on the envelope 4 in a manner already described. The two envelopes may then be transmitted through the mails from the addressor to the addressee. Upon receipt by the latter, the addressee envelope 5 is removed and the addressor envelope 4 may be remailed to the addressor, the name and address of the latter being of course, permanent on said envelope. By forming the slits 9 in the envelope 4, the corners of the addressee envelope are arranged to lie within the addressor envelope 4 and consequently, the addressee envelope is held from displacement in transit. By marking or coloring the envelope 4 adjacent the slits 9, the portions of said envelope so demarcated are indicated as the flaps under which the corners 13 of the envelope 5 fit. In this manner the addressee envelope 5 is secured to the addressor envelope without the use of extraneous fastening means of any kind and may be removed and replaced with facility by postal officials, where the contents of the addressee envelope is to be inspected.

It is to be understood that the form of my invention herein shown and described is to be taken as a preferred embodiment of the same, and that various changes in the shape, size and arrangement of parts may be made, without de-

parting from the spirit of my invention, or the scope of the appended claims.

What is claimed is:

5. A duplex envelope, including an envelope assembly, consisting of an addressor envelope having the addressor's address on one face thereof and slits formed in the said face arranged around the zone of the addressor's address, a directional legend above said address and beyond 10 said slits, one end of which issues into an arrow which terminates adjacent said indicia in the zone of the slits, and an addressee envelope secured in said slits and covering the said indicia and the head of the arrow.
15. 2. An article of manufacture of the class described, comprising an envelope having a series of slits in a wall thereof for the reception of the corners of a second envelope, said series of slits defining an area having printed thereon the name 20 and address of the addressor, said name and address being concealed by said second envelope when the latter is in place.
25. 3. A dual envelope assembly comprising two envelopes varying in size, the smaller envelope having thereon the address of the addressee and the larger envelope having thereon the address of the addressor, the said larger envelope having means to receive and removably hold the smaller envelope thereon immediately over the addressor's 30 address to normally conceal the same, whereby when the assembly is mailed, the address of the addressee is only in view, removal of the addressee envelope exposing the address of the addressor on the larger envelope to permit remailing of the 35 latter.
4. A duplex envelope assembly composed of a

large envelope and a small envelope, the large envelope being provided with the address of the sender and with slits bordering the said address and the smaller envelope having the address of the addressee and being superimposed on the larger envelope with its corners engaged in said slits and its body portion concealing the sender's address, the removal of the smaller envelope exposing the address on the larger envelope to permit remailing of the latter.

80
85

5. A duplex envelope assembly comprising a catalogue envelope having its front face marked off to define a rectangular space having a printed address in the center and a slit diagonally of each corner of the rectangle, portions of the envelope bordering the slits being colored and providing corner flaps, a smaller envelope disposed within the said rectangular space of the larger envelope with its corners inserted under the said corner flaps, said smaller envelope normally concealing the printed address on the larger envelope, the said address being exposed to permit remailing of the latter only upon removal of the smaller envelope.

90
95

6. A duplex envelope comprising a large addressor envelope provided on the front face thereof with the name and address of the addressor, a smaller addressee envelope disposed upon the said front face of the large addressor envelope and immediately over the addressor's name and address to normally conceal the same, and means for removably holding the said addressee envelope in place, the removal of the addressee envelope exposing the name and address of the addressor to permit the mailing of the addressor envelope.
